CLAIM

The ornamental design for a network storage device, as shown and described.

DESCRIPTION

FIG. 1 is a perspective view of a network storage device showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in the unlocked state;

FIG. 10 is a front view thereof in the unlocked state;

FIG. 11 is a perspective view thereof with one upper part unlocked and its handle pulled, and one lower part unlocked and its handle pulled;

FIG. 12 is a front view thereof with one upper part unlocked and its handle pulled, and one lower part unlocked and its handle pulled;

FIG. 13 is an enlarged view of the portion, labeled '13', in FIG. 9; and,

FIG. 14 is an enlarged view of the portion, labeled '14', in FIG. 9.

The dashed broken lines depict portions of the network storage device that form no part of the claimed design. The dot-dash broken lines defines the bounds of the claimed design and form no part thereof. The unevenly-spaced broken lines in FIGS. 9, 13 and 14, used to indicate portions of the figures shown enlarged, form no part of the claimed design.

1 Claim, 14 Drawing Sheets
